UNITED STATES PATENT OFFICE.

QUINCY A. ATWOOD AND LILLA D. ATWOOD, OF NEWTON, MASSACHUSETTS.

AUTOMATIC STOP FOR TALKING-MACHINES.

1,108,315.

Specification of Letters Patent. Patented Aug. 25, 1914.

Application filed September 9, 1912. Serial No. 719,316.

To all whom it may concern:

Be it known that we, QUINCY A. Atwood and LILLA D. Atwood, citizens of the United States, and residents of Newton, county of Middlesex, and State of Massachusetts, have invented an Improvement in Automatic Stops for Talking-Machines, of which the following description, in connection with the accompanying drawings, is a specification, like characters on the drawings representing like parts.

Our invention relates to talking machines and is designed to provide an improved automatic stop device for automatically stopping the machine at any desired point during or after the reproduction of the record thereby.

In the drawing of the particular embodiment of our invention selected for description and illustration, Figure 1 is a plan of a typical talking machine cabinet top, partly broken away, showing our stop in proper position thereon for use; Fig. 2, a side elevation of the device, viewed from the front 25 of the cabinet or lower side of Fig. 1, the same being set to stop the machine; Fig. 3, an elevation of the opposite side of the device from that shown in Fig. 2; Fig. 4, an end elevation from the right, Fig. 1; Fig. 5, 30 a view similar to Fig. 4 but showing the position of the parts after the stop has been actuated to stop the machine.

Our improved stop in the form herein illustrated, comprises, see Figs. 1 and 2, a base 1, of suitable material, as metal, adapted to be secured conveniently, as by screws, to the top 2 of a talking machine cabinet, said base being provided at convenient points with posts or upright plates 3 and 4. Extended to one side from the upright plate or support 3 is a shoe carrying arm 5, preferably of resilient material, and so secured to said support that it tends normally to spring toward the edge of the talking machine turn table 6, see Fig. 5. In this particular instance, the arm 5 is cut away at 7, to make it more resilient and responsive to the movement of the latch, as will be subsequently described. At a suitable point thereon the shoe carrying arm 5 is provided with a table engaging member or shoe 8, for engaging the edge of the turn or record table 6. Said

shoe is shown herein as a strip of leather, tightly fitted to and held in a tubular holder 9 secured to the arm. This shoe member 8 extends through the arm 5 and may be forced forward through said arm and holder as necessary to compensate for the wear thereof in use.

For locking the arm 5 and its shoe 8 in inoperative or table releasing position, out of contact with the table 6, we have provided said arm with a latch member 10 shown herein as a strip of suitable material as brass, folded upon itself at one, and herein in the left hand end Fig. 1, and loosely pivoted to the arm 5 by a pivot 12. One of the ends 11 of the latch is reduced in height, Figs. 2 and 3, and preferably beveled on its lower edge 13, Figs. 4 and 5, and adapted to engage a shoulder 14, or catch as a notch 15 in the plate 4. The outer or right hand end of the arm 5, Fig. 2, or a portion of the same, may be folded back upon itself to form a guide 16, Fig. 1, to receive and guide the end of the latch 10. This latch 10 serves to retain the shoe carrying arm 5 and its shoe 8 in inoperative position relative to the turn table 6. This is the normal position of the shoe carrying arm 5 where it rests until the latch 10 is released to permit said arm to throw the shoe 8 against the turn table 6.

For releasing or unlocking the latch 10, we provide a latch releasing or unlocking lever 17, Figs. 1 to 5, herein shown as pivoted to the latch 10 by the same pivot 12 that secures said latch to the arm 5. In order that this lever 17 may be engaged in different positions to release the latch and to stop the machine at different times, it is made adjustable relative to the latch 10, but it is so secured thereto, herein frictionally, that slight movement of the lever after it is set in position will release or unlock the latch and free the shoe to spring against the turn table and arrest the latter. The releasing lever is herein shown tightly gripped frictionally between the two sections of the latch 10 which are bent about and to tightly clasp it, while the latch itself together with its releasing lever are easily rotatable about the pivot 12.

The base 1 of the device is secured to the

cabinet top 2 in such position between the edges 18 thereof that the latch releasing lever 17, when positioned at any point between the extreme limits of throw, as indicated by dotted lines, Fig. 2, will be engaged by the sound arm 19 as the latter swings to the left, Fig. 1, in traveling over the record. The base must also be so positioned relative to the edge of the table 6, Figs. 1 and 4, that when the latch 10 is released, as shown in Fig. 5, the shoe 8 will press tightly against the edge of the table to restrain the same from rotating.

The point in the record at which it is desired to stop the table having been determined, for instance the inner or finishing end of the record, the needle is placed at that point on the record and the lever 17 is swung into contact with the sound arm 19, see dotted line position Fig. 1, which sets said latch lever in position to stop the machine when the sound arm in traversing the record comes into contact with it. This movement is permitted by its frictional engagement with the latch. The shoe carrying arm is now sprung back to remove the shoe from contact with the turn table which releases the latter, the shoe carrying arm being held in its released position by dropping the latch 25 behind the locking shoulder 14. The turn table and its record having been then released, the sound arm is swung to the right, as indicated in Fig. 1, and the needle placed in the outermost turn of the groove. In Figs. 1 and 2, the positions of the outer end of the sound arm at the beginning of the record and at the end of the same may be conveniently represented by the circles 20 in full and dotted line positions respectively. When the needle approaches the end of the groove in its travel over the record, the sound arm 19 in its traverse across the record will have reached the position represented by the dotted lines in Figs. 1 and 2 and at this point it will again engage the lever 17, turn it on its pivot 12 slightly to the left, and raise the latch 10 from behind the shoulder 14 permitting the resilient arm 5 to spring to the left, Fig. 5, and bring the shoe 30 against the periphery of the table to arrest it. If it is desired to arrest the record at some other point than the end thereof, the needle will, of course, be momentarily positioned at such point in the groove and the releasing arm 17 swung to the right until it contacts with the sound arm 19 in that position. The latch 10 may now be dropped behind the shoulder 14 and the sound arm returned to its outermost position and the machine started as before. When the needle reaches the point in the record at which it was momentarily positioned and which represents the point at which it is desired to

stop the machine, the sound arm will again engage the lever 17, move it and raise the latch 10 and permit the arm 5 to throw the shoe 8 against the edge of the table 6.

When it is desired to operate the machine without the automatic stop, the releasing arm 17 may be turned down or depressed in the slot 21 in the top of the plate 3, Figs. 1, 4 and 5, see dotted line position Fig. 2, below the path of travel of the sound arm 19.

This stop, although simple of construction and inexpensive to manufacture, is particularly convenient and effective, not only to stop the machine at the end of the groove or the record portion thereof, thereby preventing the needle from mutilating the face of the record in case the operator neglects to stop the machine at the proper point, or is called away therefrom while the machine is in operation, but also to stop the machine at any desired point during the reproduction of the record in case such is, for any reason, desired.

It is obvious that the talking machine may be operated using our improved stop alone, this stop answering every purpose for stopping and starting the machine, or our stop may be used in connection with the usual stop provided with the machine.

Having described one embodiment of our invention which may, however, doubtless be modified without departing from the spirit and scope of the invention, we claim:

1. A device of the class described comprising a support, a shoe carrying member movably secured thereto adapted to co-act with a rotatable member, a latch on said member and pivoted thereto, said support having a catch for the latch, a rigid latch releasing member on said latch and adapted for frictional adjustment thereon to engage a movable machine member at any predetermined time during the operation thereof.

2. A device of the class described comprising a support, a shoe carrying member movably secured thereto adapted to co-act with a rotatable member, a latch on said member and pivoted thereto, said latch member folded on itself, a rigid latch releasing lever frictionally engaged by the folds of said latch, said support having a catch for the latch, said releasing lever adapted to be positioned to engage a movable machine member at any predetermined time during the operation thereof.

3. A device of the class described comprising a support, a shoe carrying member movably secured thereto adapted to co-act with a rotatable member and provided with a rigid-frictional-lever engaging member, a latch on said lever engaging member and pivotally secured to said member and ad-

jaçent the pivoted end of said lever, said shoe carrying support having a catch for the latch, said lever adapted to be adjusted in the same plane to render inoperative said 5 shoe carrying member and also to engage a movable machine member at any predetermined time during the operation thereof. In testimony whereof, we have signed our

names to this specification, in the presence of two subscribing witnesses.

BERTHE DAVID.

It is hereby certified that in Letters Patent No. 1,108,315, granted August 25, 1914, upon the application of Quincy A. Atwood, and Lilla D. Atwood, of Newton, Massachusetts, for an improvement in "Automatic Stops for Talking-Machines," errors appear in the printed specification requiring correction as follows: Page 2, line 126, before the word "member" insert the words *shoe carrying*; page 3, line 2, strike out the words "shoe carrying"; and that the said Letters Patent should be read with these corrections therein that the same may conform to the record of the case in the Patent Office.

Signed and sealed this 29th day of September, A. D., 1914.

[SEAL.]

R. F. WHITEHEAD,
Acting Commissioner of Patents.
